(57) **CLAIM**

The ornamental design for a dental amalgam separation container, as shown and described.

DESCRIPTION

FIG. 1 is a front perspective view of a first embodiment of a dental amalgam separation container in accordance with the present invention;

FIG. 2 is a left side view thereof;

FIG. 3 is a right side view thereof;

FIG. 4 is a front view thereof;

FIG. 5 is a rear view thereof;

FIG. 6 is a top view thereof; and

FIG. 7 is a front perspective view of a second embodiment of a dental amalgam separation container in accordance with the present invention;

FIG. 8 is a left side view thereof;

FIG. 9 is a right side view thereof;

FIG. 10 is a front view thereof;

FIG. 11 is a rear view thereof; and,

FIG. 12 is a top view thereof.

The features shown in broken lines are illustrating environmental structure and form no part of the claimed design.
